UNITED STATES PATENT OFFICE.

OTTO W. SCHAUM, OF PHILADELPHIA, PENNSYLVANIA.

CENTRIFUGAL MACHINE.

SPECIFICATION forming part of Letters Patent No. 605,017, dated May 31, 1898.

Application filed November 12, 1897. Serial No. 658,284. (No model.)

To all whom it may concern:

Be it known that I, OTTO W. SCHAUM, a citizen of the United States, residing in Philadelphia, county of Philadelphia, and State of Pennsylvania, have invented certain new and useful Improvements in Hydro-Extractors; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to hydro-extractors, especially of the class as shown and described in United States Letters Patent No. 552,550, of January 7, 1896.

The object of this invention is to provide a hydro-extractor of the character above referred to with an electric motor, the shaft of the armature of said motor being directly connected to and in alinement with the shaft of the basket, thus permitting said basket to be readily and quickly started and to be brought to the speed required in a very little time, which is of great importance, especially with certain kinds of textile fabrics, as will be well understood by those familiar with the art.

The invention consists in the combination of an electric motor with my improved self-balanced hydro-extractor, the armature of said motor being carried by the shaft of the basket, while its fields are carried by the curb or casing, and in the combination and arrangement of the various parts, substantially as will be hereinafter more fully described, and finally embodied in the claim.

In the accompanying drawings, Figure 1 is an elevation of my improved hydro-extractor, the curb or casing and its supporting means being shown in section; and Fig. 2, a top plan view of Fig. 1.

In said drawings, *a* represents the curb, suitably supported by a series of brackets *bb* and intermediate adjustable suspension-rods *c*, which latter are suitably arranged in the top portions of said brackets and in the bottom flange *d* of the curb *a*, respectively. Within the curb or casing *a* is arranged the perforated basket *e*, mounted on the vertical shaft *f*, suitably supported in the bottom of

the curb or casing and also in the bearing *g*, formed at the inner end of the housing or bracket *h*, secured to and projecting from the said curb or casing *a*. The lower portion of said bracket is penetrated by a substantially horizontal rod *i*, provided at its outer end with a suitable handle *m* and at its inner end with a brake-block *n*, adapted to be moved into engagement with the inclined top flange of the perforated basket *e* when it is desired to stop the rotation of said basket.

On the top portion of the bracket *h* is adjustably arranged the arm *o*, carrying the fields *p p* of the electric motor, which fields are parallel with the bottom of the curb or casing and coöperate with the armature *q*, mounted on the shaft *s*, which shaft is in alinement and suitably coupled or connected with the shaft *f* of the basket. The shafts *f* and *s* therefore practically constitute a single jointed shaft. The other end of the shaft *s* of the armature *q* is supported in the bridge *t*, projecting from the fields *p p*, as clearly shown in the drawings. The brushes *u* for the commutator *v* are of any well-known construction and are carried by the bridge *t* in any desired manner.

From the foregoing it can be seen that the armature and its shaft are carried by the shaft of the basket, and the weight of said armature is thus uniformly distributed around the axis of the basket, and that there is no undue strain exerted in any special direction upon the said shaft, as is the case when operated by a belt and grooved pulley or by other well-known means. By this arrangement when the motor is connected with the source of electricity and the current is turned on the basket will be at its full speed in comparatively little time, and can be just as readily stopped, especially when the brake *n* is applied after the current has been shut off.

The machine can be quickly set up and readily connected with any convenient source of electricity and can be run with the least jar or tremor to the floor and at uniform speed and with very little noise.

Having thus described my invention, what I claim as new, and desire to secure by Letters Patent, is—

In a hydro-extractor, the combination with a movably-suspended curb or casing, an in-

wardly-projecting bracket secured to the top edge thereof, bearings in the free end of said bracket, an inwardly-projecting arm mounted on said bracket, electromagnets and a pair of horizontally-extending fields carried by said arm, the latter being arranged above the bearings, a bridge connecting said fields and suitably-mounted and arranged brushes and commutators, of a vertical jointed shaft 5 stepped in said curb or casing and journaled in said bearings and in the bridge, a basket carried by the lower member of said shaft and having an inclined top flange and an armature carried by the upper member of said

shaft between said fields and a brake for said basket consisting of a horizontally and longitudinally movable rod penetrating said bracket and provided at its outer end with a handle and at its inner end with a brake-block adapted to wipe on said flange, substantially 15 as described.

In testimony that I claim the foregoing I have hereunto set my hand this 9th day of November, 1897.

OTTO W. SCHAUM.
